CARD GAME INDICATOR

Leslie R. Boore, Minneapolis, Minn.

Application April 18, 1932. Serial No. 605,805

11 Claims. (Cl. 40—70)

My invention provides an improvement in card tables and is directed to a simple, easily operated, and highly efficient indicator, by the use of which there will be presented before each player a full record of the exact amount bid and trump bid upon, and preferably also whether or not the bid has been doubled or redoubled. The device is adapted to be readily applied to tables in the process of manufacture, but may also be quite readily applied to ordinary tables by a slightly remodeling thereof. Generally stated, the invention consists of the novel devices, combinations and arrangement of parts hereinafter described and defined in the claims.

15 A preferred embodiment of the invention is illustrated in the accompanying drawings wherein like characters indicate like parts throughout the several views.

Referring to the drawings:

20 Fig. 1 is a plan view showing a complete card table embodying my invention;

Fig. 2 is a view partly in plan but with some parts broken away showing the central portion of the table and illustrating the features of my 25 invention on a much larger scale than in Fig. 1;

Fig. 3 is a transverse vertical section taken on the line 3—3 of Fig. 2;

Fig. 4 is an enlarged fragmentary section taken on the line 4—4 of Fig. 2;

30 Fig. 5 is a fragmentary perspective showing a portion of an annular lock flange;

Fig. 6 is an enlarged plan view showing the central or inner operating hub and a "doubled" and "redoubled" indicator;

35 Fig. 7 is a section taken on the line 7—7 of Fig. 6; and

Fig. 8 is a section taken on the line 8—8 of Fig. 6.

The numeral 9 indicates a rectangular table 40 top which may be either a new table or a remodeled table top, but is formed on the under-side of its central portion with a large recess into which is set a large disc-like indicator-supporting plate 10 that may be of wood or any other suitable 45 material and may be made up of one or more pieces. This supporting plate structure 10, it will be noted by reference to Fig. 3, is itself recessed at its top so that it receives several indicating elements presently to be noted, with the 50 said elements slightly below the upper surface of the table top.

Located on and at the central portion of the plate 10 is a central or inner hub structure 11 formed outward of its recess with spring-containing 55 pockets 12, the tops of which are normally

closed by press buttons 13 subject to springs 14 contained in said pockets. An annular disc-like plate 15 is secured to and projects outward from the hub structure 11 and rests frictionally on the supporting plate 10. At its outer portion, this 60 annular plate 15 is formed with a raised annular indicator dial or flange 16, on the face of which are marked several groups of digits, each group running from zero to ten. These digits or numerals are preferably arranged in four groups, 65 each group occupying one quadrant of the indicator dial or flange 16 so that each of the four players will have before him what may be treated as his own indicator, but all of the indicators will give the same indication to the several players. 70

Mounted to rotate over the annular plate 15 between the centrally located operating hub 11 and the annular indicating flange 16 is an annular outer operating hub 17, which, like the central hub 11, is provided with pockets 18, the tops of 75 which are normally closed by press buttons 19 subject to springs 20 contained in said pockets, see particularly Fig. 4. Rigidly secured to and projecting outward from an annular hub 17 is an annular dial or indicating flange 21, on which is 80 marked in four groups the suit-indicating characters, to wit: spade, heart, diamond, club and "no trump". The marked annular dial 16 may be conveniently designated as the "bid amount" indicator, while the marked dial 21 may be indicated as the "suit" indicator; and from what 85 has been said, it is obvious that both of said indicators are arranged so that each of four players will have before him his own individual indicator for both of the above noted features. 90

To cover all but one of the characters of the dial 16 and all but one of the characters of the dial 21 of any particular group of indicating devices, a cover plate or sheet 22 is extended over the dials 16 and 21 and up to the outer annular 95 operating hub 17, which latter, as shown, is provided with a flange that projects over the inner edge of said cover. This cover 22 may be a part of an original table or may be a separate sheet or plate independently formed and applied to the 100 table top proper, but is provided with sight openings or small windows 24, one for each player, through which the characters of both of the indicators 16 and 21 may be presented to view. Preferably these sight openings 24 will cover 105 with a transparent material such as cellophane indicated at 25.

Inasmuch as the annular operating hub 17 rests upon the rotatable plate 15 and would be frictionally moved when the latter is moved to ad- 110

just the dials 16, suitable latch devices are applied to the depressible push buttons 19, see particularly Fig. 4. These push buttons 19 are provided with projecting pins or like elements 26 that normally engage notches 27 of an annular latch plate 28 that is secured to the inner edge of the cover plate 22, see Figs. 3 and 5. Since the plate 15 has very extended engagement with the plate 10, accidental movement thereof will not be produced by rotation of the annular operating hub 17.

When the dial 16 is to be adjusted, the operator places a finger on each of the push buttons 13 so that the fingers get a good grip on the central operating hub 11 and so that by the operation of the fingers, said central hub can be rotated to set the dial 16 in the proper indicating position. When the dial 21 is to be adjusted the operator likewise depresses the two push buttons 19 so as to first release the latch pins 26 from the notches 27 of the latch plate 28 and then, as is evident, by rotation of said hub 17, the dial 21 may be properly set and relatched in its set position.

25 Directing attention now particularly to Figs. 6, 7 and 8, which show the "doubled" and "redoubled" indicator, it will be noted that the central operating hub 11 is a hollow box-like structure formed in its top with a rectangular opening 29 and formed at its longitudinal edges with down-turned guide flanges 30. By reference particularly to Figs. 7 and 8 it will be noted that the plate 32 at its side edges is arranged to slide under the upper portion of the flanges 30 and is thereby held against upward displacement but free for the sliding movements described. The numeral 31 indicates a bowed spring intermediate secured centrally to the bottom of the hub structure 11 and provided with free ends normally under spring tension to move upward into the extremities of the slot 29. The ends of this bowed spring 31 are marked one with the word "doubled" and the other with the word "redoubled". Mounted to slide on the free ends of the spring 31, but guided by the flanges 30 is a cut-off plate 32 which when moved to one extreme position shown in Fig. 7, will uncover the word "redoubled" and cover up the word "doubled", but which when slid into its other position, will uncover the word "doubled" and cover up the word "redoubled". When the plate 32 is moved to an intermediate position, it will cover up both the words "doubled" and "redoubled" and that of course will be its normal position. These several indicators give the players of the game the best kind of indication of the conditions under which they are playing the particular hand. The device shown in detail in Figs. 6, 7 and 8, is especially useful in playing bridge, but the other indicating features will be found serviceable in playing various other card games or, generally stated, all card games where it is desirable to keep before the players not only the amount bid but the trump bid upon. On the corners of the board illustrated in Fig. 1, I have shown pads 33 containing the rules of the game and a score pad 34, which features, while convenient, do not form part of the present invention.

70 From the foregoing, it is evident that the preferred form of the device illustrated is capable of various modifications as to details of construction and arrangement of parts within the scope of the invention herein disclosed and claimed.

What I claim is:

55 1. A card game indicator comprising a sup-

porting board, and mounted thereon, a centrally located inner operating hub, having an extended plate terminating in an annular dial having digits marked thereon for indicating the amount of bids, an annular operating hub surrounding said centrally located hub and provided with an annular dial marked with characters indicating the suit or trump bid upon, said hubs having independently exposed surfaces providing means to independently move the said two indicating dials by manual operation.

2. A card game indicator comprising a supporting board, and mounted thereon, a centrally located inner operating hub, having an extended plate terminating in an annular dial having digits marked thereon for indicating the amount of bids, an annular operating hub surrounding said centrally located hub and provided with an annular dial marked with characters indicating the suit or trump bid upon, said hubs having independently exposed surfaces providing means to independently move the said two indicating dials by manual operation, and a plate covering said dials but having at least one sight opening arranged to expose at one time one character of each of said dials.

3. The structure defined in claim 2 in which the characters on said dials are arranged in repeating groups and said cover is provided with sight openings one for each of said groups.

4. A card game indicator comprising a supporting board, and mounted thereon, a centrally located inner operating hub, having an extended plate terminating in an annular dial having digits marked thereon for indicating the amount of bids, an annular operating hub surrounding said centrally located hub and provided with an annular dial marked with characters indicating the suit or trump bid upon, said hubs having independently exposed surfaces providing means to independently move the said two indicating dials by manual operation, and releasable latch means holding said annular hub and its connected dial against rotation.

5. A card game indicator comprising a supporting board, and mounted thereon, a centrally located inner operating hub, having an extended plate terminating in an annular dial having digits marked thereon for indicating the amount of bids, an annular operating hub surrounding said centrally located hub and provided with an annular dial marked with characters indicating the suit or trump bid upon, said hubs having independently exposed surfaces providing means to independently move the said two indicating dials by manual operation, a depressible button applied to said annular hub, and latch means normally holding said annular hub against rotation and comprising a notched annular flange secured adjacent said annular hub and a projection from said button normally engaging said notched flange but releasable therefrom when said button is pressed.

6. The structure defined in claim 5 in which said button when pressed is below the exposed surface of said annular hub and opens a hole giving the finger a good grip on said hub.

7. The structure defined in claim 1 in which said central hub has applied thereto a shiftable "doubled" and "redoubled" indicator.

8. The structure defined in claim 1 in which said central hub has applied thereto a shiftable "doubled" and "redoubled" indicator, and comprising a slide normally covering both of said indicators but shiftable to uncover either thereof.

at will, and a spring-acting member normally pressing said slide and having on the extremes thereof the said indications "doubled" and "re-doubled".

5 9. The structure defined in claim 2 in which said annular hub is supported on the projecting plate of said central hub.

10 10. The structure defined in claim 2 in which said annular hub is supported on the projecting

plate of said central hub, and releasable latch means normally holding said annular hub against rotation with said central hub.

11. The structure defined in claim 2 in which said hubs are provided with openings normally closed by spring pressed buttons, which when depressed afford good finger grips for the rotation of said hubs and the parts adjusted thereby.
